UNITED STATES PATENT OFFICE

EDWARD TIMBS, OF LOS ANGELES, AND LEWIS E. ZERBE, OF MONETA, CALIFORNIA,
ASSIGNORS TO THE NATIONAL SUPPLY COMPANY OF DELAWARE, OF NEW YORK,
N. Y., A CORPORATION OF DELAWARE

TWO-POST, TWO-SPEED, THREE-SHAFT PORTABLE DRAWWORKS

Application filed October 24, 1927. Serial No. 228,158.

This invention relates to rotary drawworks, such as are employed in the drilling of wells for gas, oil, and the like, and is more particularly related to a rotary drawworks of comparatively light, compact structure adapted to be used in connection with a portable drilling outfit or the like and which may be readily transported from position to position, as desired.

- 10 In the construction of drawworks for use in connection with the apparatus employed for drilling wells, and particularly oil wells, three major problems present themselves, the first of which is to provide a construction 15 which is compact so that the operative parts of the drawworks will not be moved too far from the center of the drilling rig and the rotary machine mounted axially of the hole being drilled. The second problem which 20 presents itself is to provide a construction which is relatively inexpensive and which is rigid or sturdy and will support relatively heavy loads such, for example, as long strings of casing, drill stems, and the like. The third 25 problem is to provide a drawworks construction which is relatively flexible and will permit operation from a single point in the well rig and which provides a plurality of speeds so as to enable the driller to control the opera- 30 tion of the same, depending upon the kind of formation being drilled through, the particular drilling operation in progress and in the construction of a portable drawworks, the provision of a structure which is not too 35 heavy and which may be entirely mounted upon skids or the like so as to permit the same to be moved as a unit.

It is, therefore, an object of this invention to provide a rotary drawworks which is of 40 compact structure, which will provide a satisfactory range of flexibility and which includes a pair of posts and supporting beams upon which the drum shaft, line shaft, and a counter shaft are rotatably supported, there 45 being means connecting the shafts in driven and driving relation so as to provide the compact and flexible structure desired.

Another object of this invention is to pro- 50 vide a rotary drawworks including a base structure on which a pair of posts are sup-

ported and between which beams are secured, the drum shaft is rotatably supported by the posts, and the line shaft and counter-shaft are rotatably supported by the said beams, there being also means for connecting the said shafts in driven and driving relation so as to permit of relatively great flexibility of opera- 55 tion.

Another object of this invention is to pro- 60 vide a rotary drawworks including three shafts mounted upon a frame structure including two posts and between which shafts driving means are provided to provide a two-speed drive for the drum shaft of the rotary drawworks, the drum of the rotary draw- 65 works being loosely journaled on the drum shaft to permit the same to turn freely without requiring operation of the connecting and driving means between the shafts, the entire structure being so formed as to permit the 70 same to be mounted on skids or the like to provide a unit structure which is readily transportable.

Other objects and advantages of this invention, it is believed, will be apparent from the 75 following detailed description of a preferred embodiment thereof, as illustrated in the drawings.

In the drawings:

Figure 1 is a top plan view of a rotary 80 drawworks embodying this invention.

Figure 2 is a front elevation thereof, cer- 85 tain parts being broken away.

Fig. 3 is a side elevation thereof.

In the preferred embodiment of this invention, as illustrated in the accompanying drawings, 1 and 2 designate base ship-channels which form longitudinally extending skids upon which the entire drawworks is mounted. The ship-channels 1 and 2 are secured together at their opposite ends by means of transversely extending frame channel irons 3 and 4. Secured to the forward ends of the base ship-channels 1 and 2 are substantially upright posts 5 and 6. The posts 5 and 6 are secured to the channels 1 and 2 by means of plates 7 in position slightly inclined forwardly from the vertical. 90

A jack shaft and line shaft supporting 95 frame is provided at the rear of the posts 5 100

and 6 by brace ship-channels 8 and 9 which are connected at their lower ends to the channels 1 and 2, respectively, by means of plates 10 and at their upper ends to the posts 5 and 6, respectively, by plates 11. The posts 5 and 6 are secured together at or near their upper ends by means of angle irons 12 and 13, which are secured at their opposite ends to the posts 5 and 6. This manner of frame construction for the rotary drawworks provides a rigid frame for supporting the operative mechanism of the drawworks so as to provide a frame which may be easily transported from position to position as desired without necessitating the securing of any of the frame portions to the derrick of the well in order to align other parts thereof with the operative mechanism being employed for the drilling of the well, as has heretofore been the custom by providing a drawworks including a frame structure that first had to be accurately positioned in the well in definite relation to the rotary drawworks, crown block and the like, thereof.

25 A drum shaft 14 is supported on the front faces of the posts 5 and 6 in bearings 15 and 16, which are preferably of the self-aligning type. Mounted on the drum shaft is a drum 17 which may be of any suitable or desirable construction. The drum 17 is herein illustrated as including a spool portion 18 having integral flanges 19 formed at its opposite ends and bearing race portions 20 within which roller bearings 21 are mounted to journal the drum 17 on the shaft 14. The shaft 14 is driven by means of a sprocket 22 which is secured thereto between the post 5 and the flange of the drum 17 at this end of the drawworks. In order to hold the drum 17 properly positioned upon the shaft 14 and to prevent endwise motion of the same, a spacer collar 23 is mounted between the hub of the sprocket 22 and the bearing race portion 20 of the drum 17.

40 Means are provided for engaging the drum 17 with the shaft 14, which means preferably comprises a clutch 24 of the jaw type permitting the drum 17 to be engaged with the shaft 14 to rotate the drum 17 in either direction. The clutch jaw faces of the clutch 24 are preferably formed integral with one of the bearing race portions 20, as indicated at 25, and on the adjacent face of a clutch collar 26 which is slidably splined on the shaft 14 in such a manner as to substantially fill the shaft 14 between the posts 5 and 6 so that at this end of the shaft 14 the drum is also prevented from moving longitudinally of the shaft.

45 Any suitable or desirable form of means may be provided for actuating the clutch collar 26, which means are herein illustrated as comprising a yoke 27 which engages within the race 28 formed in the clutch collar and is pivotally mounted by a pin 29 on a bracket

30 secured to the post 6. The clutch collar 26 by this manner of construction extends into the brake drum 31, secured to the flange 19 of the drum 17 adjacent the post 6, thereby permitting the spool 18 of the drum to be formed of a maximum length determined by the distance between the posts 5 and 6. The yoke 27 is pivotally secured by a pin 32 to a rod 33 which in turn is pivotally secured by the pin 34 to the arm 35 of an actuating pedal 36. The actuating pedal 36 is pivotally mounted on a shaft 37 secured to the frame member 4.

50 Mounted in bearings 38 and 39 at the upper ends of the channel irons 8 and 9 is a line shaft 40. This shaft is in a vertical plane displaced laterally from a line joining the posts. The bearings 38 and 39, like the bearings 15 and 16, and the bearings 41 and 42 within which the jack shaft 43 is journaled at the lower ends of the channels 8 and 9 may all be of the self-aligning type.

55 The line shaft 40 is driven through either of the sprockets 44 or 45 from any suitable or desirable engine, motor or the like, as is commonly employed for the driving of rotary drawworks. The sprockets 44 and 45 are provided and are of different diameters and have different numbers of teeth formed thereon so as to permit the line shaft 40 to be driven at different speeds. Means are provided for driving the jack shaft 43 from the line shaft 40, which means preferably comprise sprockets 46 and 47 which are journaled upon the line shaft 40. Clutches 48 and 49 are provided for engaging the sprockets 46 and 47, respectively, with the line shaft 40. The jack shaft 43 is driven from the line shaft 40 by means of chains, not shown, from the sprockets 46 and 47 to sprockets 50 and 51 secured to the jack shaft 43. The drive provided by the sprockets 46 and 50 provide a high speed drive, and the drive provided by the sprockets 47 and 51 provide a low speed drive. In order to permit the drive connection between the line shaft 40 and the jack shaft 43 to be made so that the jack shaft 43 may be driven in either direction from the line shaft 40, the clutch 48 is preferably of the jaw type. In order to permit the jack shaft 43 to be driven from the line shaft 40 when the line shaft 40 is in motion, the clutch 49 is preferably of the spiral type.

60 Secured to the jack shaft 43 is a drum shaft drive sprocket 52 by means of which the drum shaft 14 is driven by a chain, not shown, trained over the sprocket 22 secured to the drum shaft 14.

65 The rotary machine is preferably driven directly from the line shaft 40 so that when it is desirable only to actuate the rotary machine, none of the other operative parts of the rotary drawworks are required to be in motion. For this purpose, a sprocket 53 is

journaled on the line shaft 40 and a clutch 54 of any suitable or desirable type is provided for engaging the sprocket 53 with the line shaft 40. The rotary machine, not shown, is driven from the sprocket 53 by means of a chain likewise not shown, but in a manner well understood in the art.

Cat heads 55 and 56 of any suitable or desirable form are secured to the line shaft 40 on the outside of the posts 5 and 6, respectively.

Brake means are provided which may be of any suitable or desirable type or form of construction and are herein illustrated as comprising the brake drum 31 and the brake drum 57 which are secured to the opposed flanges 19 of the drum 17. Mounted on the brake drums 31 and 57 are brake bands 58 which are actuated by any suitable or desirable form of means such, for example, as the control illustrated at 59 at the rear of the drum 17. Any suitable or desirable form of means such as is well understood in the art may be provided for actuating the respective clutches mounted on the line shaft 40. Means for actuating clutches of this type are so well understood in the art that it is not deemed necessary to particularly point out and describe the same.

By placing the bearings for the line shaft 40 on the inclined braces or struts 8, the drawworks is made more compact, at the same time permitting the necessary distance between the line shaft and the drum shaft 14. The lowering of the level of the line shaft 40 is also advantageous, because it lowers the line of pull of the drive chain for driving the line shaft from the engine. This greatly reduces the strains on the frame of the drawworks and enables a lighter frame to be employed. It also reduces the vibration effects on the drawworks from the drive chain. It also has the desirable effect of shortening the length of the drive chain from the line shaft to the jack shaft.

Having fully described our invention, it is to be understood that we do not wish to be limited to the details herein set forth, but our invention is of the full scope of the appended claims.

We claim:

1. In a rotary drawworks, the combination of a frame structure including a pair of spaced base frame members, substantially upright posts secured to the base frame members, a pair of inclined brace frame members secured at their ends to the posts and the base frame member, a drum shaft, means for rotatably supporting the drum shaft on the posts, a line shaft, means for rotatably supporting the line shaft on the brace frame members on a vertical line removed laterally from a line joining the posts, a jack shaft, means for rotatably supporting the jack shaft on the brace frame members below the

line shaft, means for driving the line shaft, means for driving the jack shaft from the line shaft, and means for driving the drum shaft from the jack shaft.

2. In a rotary drawworks, the combination of a frame comprising two triangular end frames having diagonal back brace members, and including a pair of substantially upright spaced posts connected to the brace members, a drum shaft rotatably supported on said posts, a line shaft rotatably journaled in bearings on said frame above the drum shaft and on a vertical line removed laterally from a line joining the posts, a jack shaft rotatably journaled in bearings on said back brace members below and to the rear of the drum shaft, means for driving the line shaft, a multiple speed drive means from the line shaft to the jack shaft, and means located between said end frames for driving the drum shaft from the jack shaft.

3. In a rotary drawworks, the combination of a frame consisting of two triangular end frames with diagonal back brace members and forward posts connected to the brace members, a drum shaft journaled in bearings on the posts, a line shaft rotatably supported in bearings on the brace members above and toward the rear side of the drum shaft, a jack shaft journaled in bearings on the brace members to the rear of the drum shaft, and mechanism located between said end frames including means for driving the line shaft, a rotary drive sprocket journaled on the line shaft, clutch means for releasably connecting the rotary drive sprocket to the line shaft, a low speed drive connection from the line shaft to the jack shaft, a higher speed drive connection from the line shaft to the jack shaft, clutches on the line shaft for the low and higher speed drive connections, means for driving the drum shaft from the jack shaft, a drum journaled on the drum shaft, and clutch means for releasably securing the drum to the drum shaft.

4. In a rotary drawworks, the combination of a frame comprising two triangular end frames with diagonal back brace members, a drum shaft journaled in bearings on the frame, a line shaft rotatably supported in bearings on the diagonal back brace members above the drum shaft and located in a plane removed laterally from the vertical plane passing through the drum shaft, a jack shaft journaled in bearings on the diagonal back brace members to the rear of the drum shaft, means for driving the line shaft, means for driving the jack shaft from the line shaft, and means for driving the drum shaft from the jack shaft.

Signed at Torrance, California, this 13th day of October, 1927.

EDWARD TIMBS.
LEWIS E. ZERBE.
